ATTORNEYS.

UNITED STATES PATENT OFFICE.

GEORGE H. BIRD, OF BROOKLYN, NEW YORK.

SPOOL.

Application filed July 24, 1925. Serial No. 45,801.

To all whom it may concern:

Be it known that I, GEORGE H. BIRD, a citizen of the United States, and a resident of Brooklyn, in the county of Kings and State of New York, have invented new and useful Improvements in Spools, of which the following is a specification.

This invention relates to spools for receiving ribbon and other narrow fabrics as it is usual to prepare them for sale, and more particularly to such spools including a body upon which the ribbon is wound and separate end flanges secured to opposite ends of said body to retain the ribbon thereon.

One object of the invention is to provide a spool of the character described embodying novel and improved features of construction for securing said end flanges to the body.

Other objects are to provide in a spool of this character a novel and improved combination of a metal tube and means to cooperate with said tube for obtaining a strong, durable and easily produced assembly of the body and the end flanges of the spool; to thus provide in such a spool a body having an axial opening to loosely receive said metal tube, and flanged bushings or thimbles to fit the ends of said tube and interposed between the tube and said body and said end flanges, the ends of the tube being upset or expanded to clamp against said end flanges on said body, and to obtain other results and advantages as may be brought out by the following description.

Referring to the accompanying drawings, in which the same reference characters designate corresponding and like parts throughout the several views,

Figure 1 is a longitudinal vertical sectional view through a spool embodying the invention;

Figure 2 is a side elevation thereof;

Figure 3 is a fragmentary transverse sectional view through a modified form of spool;

Figure 4 is a transverse sectional view, taken on the line 4—4 of Figure 3;

Figure 5 is a view similar to Figure 3 showing another modification of the invention;

Figure 6 is a similar view showing a still further modified form of the invention;

Figure 7 is a detached composite perspective view of the tubular rivet and thimbles;

Figure 8 is a detached perspective view of a modified form of rivet tube, and

Figure 9 is a fragmentary end view of a spool including a tubular rivet such as shown in Figure 8.

Specifically describing the embodiment of the invention shown in Figures 1 and 2, the reference character 1 designates a drum formed of any suitable material such as cardboard and upon which is adapted to be wound the ribbon or the like, said drum having alined axial openings 2 in the ends thereof. End flanges 3 of any suitable material such as cardboard, are applied to opposite ends of the drum 1, said flanges being of greater diameter than the drum 1 so as to retain the ribbon upon the drum. The flanges 3 are formed with axial openings 4 to register with the opening 2 in the ends of the drum 1. For securing the flanges 3 to the ends of the drum, I utilize a metal tube 5 to loosely pass through the openings 4 and 2 in the flanges and drum respectively. upon each end of the tube 5 is fitted a thimble or flanged bushing 6 the body of which projects into the openings 2 and 4 and the flange 7 of which bears against the outer surface of the corresponding end flange 3, the end of the body having the flange being flared or rounded as at 50. The ends of the tube 5 are nicked or expanded outwardly as indicated at 8, into the flared portion 50 and, against the flange 7 of the corresponding thimble 6. With this construction, the flanges 3 are firmly clamped against the ends of the drum 1 between the drum and the flanges 7 of the thimbles 6, and the upset ends 8 of the tube 5 hold the thimbles in tight engagement with the end flanges 3 of the spool. The ends of the tube 5 are disposed inwardly of the planes of the flanges 7 so as to permit the spools to be closely packed end to end. The tube 5 is thus substantially a metal tubular rivet, and the thimbles 6 reinforce the ends of the tube during the expanding operation, prevent injury to the flanges 3 and the drum 1 and provide an extended bearing on the flanges 3 around the openings 4 which prevents tearing of the flanges from the thimbles and reinforces the spool at its axis.

In some instances, the pasteboard of which the drum 1 and flange 3 may be formed is so flexible as to bend inwardly or collapse as the ends of the tube 5 are upset,

- and accordingly I may utilize a metal sleeve 9 upon which the drum 1 is mounted and which in turn receives the thimbles 6 and the tube 5, as shown in Figure 3 of the drawings. The sleeve 9 is preferably of a length to project beyond the ends of the drum 1 a distance slightly less than the thickness of the end flanges 3 of the spool, and accordingly when the ends of the tube 5 are upset, 5 the ends of the sleeve 9 reenforce the structure so as to prevent collapsing of the ends of the drum and the flanges 3. Furthermore, the sleeve 9 reinforces the spool at its center. 10
- 15 A similar effect may be accomplished by the use of a wooden core or bushing 10, as shown in Figure 5 of the drawings. This wooden core may be of a length only sufficient to pass through the axial openings in 20 the drum 1, and the thimbles 6 clamp the end flanges 3 of the spool directly against the ends of the core 10. With a wooden core such as the core 10, the drum 1 may in some cases be dispensed with and the ribbon wound directly upon the core. Such a construction would be identical with that 25 shown in Figure 5, with the drum 1 removed.

Another modified form of the invention 30 is shown in Figure 6 of the drawings, in which the body of the spool comprises a tube 11 of pasteboard within the ends of which are fixed wood, metal or pasteboard bushings 12, the openings in which are 35 adapted to loosely receive the tubular rivet 5 and the thimbles 6, substantially as does the sleeve shown in Figure 3 of the drawings. The end flanges 3 of the spool are clamped between the flanges 7 of the thimbles and the ends of the body 11. The body 11 may have the ribbon directly wound thereon, or a drum having the ribbon wound thereon may be fitted upon the body 11 in a manner similar to that illustrated in Figure 5. 40

45 To facilitate the assembly of the spool, and particularly to expedite the upsetting of the ends of the tubular rivet, said ends may be notched as at 13 (see Figure 8), whereby a plurality of ears 14 are provided. To secure the body of the spool and the flanges upon the tube 15, the ears 14 may be bent outwardly, as shown in Figure 9, against the flange 7 of the corresponding thimble 6, the tongues thus serving the same effect as the upset or flared end of the tube shown in Figures 1-6, inclusive.

50 A spool constructed in accordance with the invention may be easily and quickly assembled, is inexpensive to manufacture, and is strong and durable. No glue is necessary, and substantially the only mechanical operation is the upsetting of the ends of the tubular rivet 5 or 15.

55 It will be understood that the particular details of construction illustrated and de-

scribed are mainly for the purpose of explaining the principles of the invention, and that changes and modifications in these details may be made by those skilled in the art without departing from the spirit or 70 scope of the invention. Therefore, I do not desire to limit myself except as required by the following claims when construed in the light of the prior art.

Having thus described the invention, what 75 I claim is:

1. A spool comprising a body having an axial opening, end flanges for said body having openings coaxial with said opening in the body, a metal tube arranged in said openings, and a thimble fitted exteriorly upon each end of said tube with one of said flanges between it and said body, the ends of said tube being expanded into said thimbles to clamp said flanges against said 85 body.
2. A spool comprising a body having an axial opening, end flanges for said body having openings coaxial with said opening in the body, a metal tube arranged in said openings, and a thimble fitted exteriorly upon each end of said tube with its body arranged in said openings and its flange overlying the outerside of one of said end flanges, the ends of said tube being upset 95 over said thimbles to clamp said end flanges between said thimbles and said body of the spool.
3. A spool comprising a pasteboard drum having an axial opening, a rigid core arranged in said opening and having an opening coaxial with said drum, end flanges for said drum having openings coaxial therewith, and a metal tube extending through said opening in the core and having its ends 10 expanded to clamp said end flanges against the ends of said core.
4. A spool comprising a body having an axial opening, a core arranged in said openings of said body and having an opening coaxial with said body, end flanges for said body having openings coaxial with said body, a thimble fitted in each end of said opening in said core with one of said end flanges between it and said core, and a metal tube extending through said thimbles and having its ends upset thereover to clamp said end flange against said core.
5. A spool comprising a pasteboard drum having an axial opening, a rigid core arranged in said opening and having an opening coaxial with said drum, end flanges for said drum having openings coaxial therewith, a thimble fitted in each end of said opening in said core with one of said end flanges between it and said core, and a metal tube extending through said thimbles and having its ends upset thereover to clamp said end flange against said core.
6. A spool comprising a body having an 13

axial opening, end flanges for said body having openings coaxial with said opening in the body, a metal tube arranged in said openings, and a thimble fitted exteriorly upon each end of said tube with its body arranged in said openings and its flange overlying the outerside of one of said end

flanges, the end of the thimble body adjacent the flange being flared and the ends of said tube being expanded into the flared portion of said thimbles to clamp said end flanges between said thimbles and said body of the spool. 10
